Primary Examiner — Adir Aronovich(74) *Attorney, Agent, or Firm* — Sughrue Mion, PLLC(57) **CLAIM**

The ornamental design for a camera body, as shown and described.

DESCRIPTION

FIG. 1 is a top, front and right side perspective view of a camera body showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a top, front and right side perspective view thereof with a lens attached.

The portions of the camera body in broken lines are shown for illustrative purposes only and form no part of the claimed design.
